Primary Examiner — T. Chase Nelson*Assistant Examiner* — Kathleen M Sims(74) *Attorney, Agent, or Firm* — Norris McLaughlin & Marcus PA(57) **CLAIM**

The ornamental design for a detergent dispensing device lid, as shown and described.

DESCRIPTION

FIG. 1 is a front perspective view of my detergent dispensing device lid

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and,

FIG. 7 is a bottom plan view thereof.

The broken line showing of details in FIGS. 3, 4, and 5 is included for the purpose of showing environmental structure. The broken line structure of FIG. 7 represents a boundary line. The broken line structure in FIGS. 1 and 6 serves as a boundary line. The dashed line interior oval shape in FIG. 6 represents environmental structure. These dashed lines represent no part of the claimed design for a detergent dispensing device lid.
